(57) **CLAIM**

The ornamental design for a tray cover, as shown and described.

DESCRIPTION

FIG. 1 is a perspective view of a tray cover showing my new design.

FIG. 2 is a left elevation view of the tray cover of FIG. 1.

FIG. 3 is a right elevation view of the tray cover of FIG. 1.

FIG. 4 is a front elevation view of the tray cover of FIG. 1.

FIG. 5 is a rear elevation view of the tray cover of FIG. 1.

FIG. 6 is a top plan view of the tray cover of FIG. 1.

FIG. 7 is a bottom plan view of the tray cover of FIG. 1; and,

FIG. 8 is a plan view of the tray cover of FIG. 1 shown in an unfolded configuration.

The broken lines showing cans and a bottom tray represent environmental structure. All other broken lines represent portions of the tray cover. The broken lines form no part of the claim.
